UNITED STATES PATENT OFFICE.

EUGENE ROBINSON, OF DETROIT, MICHIGAN.

RAILWAY-TIE.

SPECIFICATION forming part of Letters Patent No. 447,356, dated March 3, 1891.

Application filed June 20, 1890. Serial No. 356,059. (No model.)

To all whom it may concern:

Be it known that I, EUGENE ROBINSON, a citizen of the United States, residing at Detroit, county of Wayne, State of Michigan, have invented a certain new and useful Improvement in Railway-Ties; and I declare the following to be a full, clear, and exact description of the invention, such as will enable others skilled in the art to which it pertains to make and use the same, reference being had to the accompanying drawings, which form a part of this specification.

My invention is designed to produce a metallic railway-tie which shall be of such construction that it can be cheaply manufactured and will be effective in use and very durable; and it consists of a combination of devices and appliances hereinafter described and claimed.

20 In the drawings, Figure 1 is a side elevation of a portion of the tie. Fig. 2 is a plan view of one end with the rail attached. Fig. 3 is a plan view of the tie itself with the rails and fastening devices removed. Fig. 4 shows the 25 rail-fastener bolt.

In carrying out the invention, A represents the tie proper, and B the rail. As will be observed, the tie has a peculiar shape, being wide or fan-shaped at the portions a , and the 30 edges converging toward the center where the metal is twisted, as shown in Figs. 1 and 3 at a' . At the part a the metal is bent to form an upright portion a^2 , and again bent to form a horizontal portion a^3 . It is on the 35 horizontal portion a^3 that the rail B rests.

C is the clamp or fastener for holding the rail in position. Its shape is peculiar, as shown in Fig. 4, there being a lip or projection c for engaging over the flange of the rail, while the 40 main portion c' projects horizontally underneath the rail. A bolt c^2 is formed integral with this portion c' .

D is the clamp for the opposite flange of the rail.

45 A bolt-orifice is provided in the upright portion a^2 of the tie, through which the bolt c^2 may pass, and a slot a^4 is provided in the horizontal portion a^3 of the tie. Now by inserting the block C in the slot a^4 , so that the 50 lip c will engage on the flange of the rail and extending the bolt c^2 through the orifice in the upright portion a^2 of the tie and through

a bolt-orifice in the fastener D, the parts may be engaged together by the nut c^3 .

One or more washers E may be provided 55 between the end of the block c' and the upright portion a^2 of the tie, whereby the gage of the rails may be exactly regulated.

It will be observed that the twisted portion a' centrally between the extremities of the 60 tie is raised to a higher elevation than the portions a where the latter join the upright portions a^2 —that is, the twisted portion is brought up adjacent to the surface of the ballast, thus forming a hip or angle. By this 65 construction any lateral or endwise motion of the tie is prevented, since a bearing is formed not only against the upright portion a^2 , but against the portion a , because of its being at an angle with the surface. By twisting the 70 metal at the middle, as shown, the tendency of this middle portion to sink to a level with the ends is prevented, and the tie greatly strengthened by this twisting. So, also, the 75 widened or fan-shaped ends present a broad surface and effectively bear the weight on the rails. It will also be observed that by the peculiar clamping of the rail to the tie the rail can be held securely in place without 80 liability of becoming loose.

It is of course obvious that, instead of twisting the metal at the middle of the tie, as shown, the same effect will be accomplished by upsetting the edges of the metal or making the middle portion extend at right angles 85 to the main portion. It is also obvious that, if desired, I might form the fastener or clamp D integral with the tie—that is, provide a lug on the upright portion a^2 of the tie, against which the inner flange of the rail might bear. 90 This would, of course, be the equivalent of the clamp D, and I would be understood as covering it by my invention.

What I claim is—

1. A metallic railway-tie bent into the upright portions a^2 and arched centrally between such portions to form the middle a' at a higher level than the lower parts of such upright portions, substantially as described.

2. A metallic railway-tie bent to form the upright portions a^2 and having the elevated, twisted, or upset portion a' centrally between such upright portions, substantially as described.

3. A metallic railway-tie bent to form the upright portions a^2 and outwardly-extending horizontal portions a^3 , and having centrally between such upright portions the elevated twisted portion a' , substantially as described.

4. In a metallic railway-tie, the combination, with the upright portion a^2 and horizontal portion a^3 , of a combined rail clamp and bolt C, formed as shown, whereby the rail is firmly clamped to the tie, substantially as described.

5. The combination, with a metallic tie hav-

ing the upright portion a^2 and horizontal portion a^3 , provided with the slot a^4 , of the combined clamp and bolt C and clamp or fastener D for clamping the rail firmly to the tie, substantially as described. 15

In testimony whereof I sign this specification in the presence of two witnesses.

EUGENE ROBINSON.
